UNITED STATES PATENT OFFICE.

MAX RICHARD JOHANN SCHMID, OF BUENOS AIRES, ARGENTINA.

PRODUCING REFINED SUGAR.

No Drawing. Application filed April 2, 1926, Serial No. 99,403, and in Argentina February 5, 1926.

In the present method of producing refined sugar there are two stages entirely distinct one from the other, although both may be carried out in the same establishment. 5 One is the production of crude cane sugar, or beetroot sugar, the other the transformation of this into refined sugar. This method of procedure has for its basis certain principles, in regard to the means to be employed, so deeply rooted that they partake of the nature of axioms. And these are: firstly, that it is only possible to produce a sugar which is really white by the employment of bleaching carbons; secondly, that 10 the quantities of these which must be employed are so large that the raw material, in this case the raw sugar, has to be purified to a certain extent beforehand, otherwise the cost of the bleaching agent would be 15 commercially prohibitive. These basic principles are founded upon conceptions of universal acceptance, as regards the effects of the means employed, whatever may be the actual process used. 20 The process for which this patent is sought to be granted is characterized by being the consequence of a radical change in the above mentioned conceptions. From this it results that, using to begin with the same means, but in a different combination, and arriving by its intermediary at quite 25 distinct results, what have been hitherto axiomatic difficulties have been overcome. The new process allows of the two stages at present necessary in the refining of sugar to be united into one stage, at a greatly reduced cost, that is to say, it permits of very economical production of sugars refined straight from the concentrated juice of the 30 cane or from sugar beetroot, and also the perfect refinement of sugars of a very inferior quality. The fundamental idea of the new process is the following: The animal or vegetable carbon commonly used in sugar refining has as its principal quality its capacity for absorption, and not its bleaching properties. In other words, these carbons are absorbents par excellence for certain salts, whereas their bleaching property is very small, it being the other ingredients, commonly used, which really possess the bleaching effect, an effect of which very little advantage is taken today, owing to the fact that the decolorization of the sugar 35 syrups is produced chiefly by the formation of salts which are subsequently ab- sorbed by the carbons. In consequence of these new ideas, the manufacture of refined sugar, whether directly from sugar cane juices or from sugar beetroot, or from sugar 40 of inferior quality, undergoes a complete change, and a result is achieved, in a most economical manner, which hitherto has been, if not technically impossible, at least commercially prohibitive. By the new 45 process, one may, for example, produce in this country refined sugars either directly from sugar cane juices or from sugar beetroot, at an additional cost of one half a cent per kilo or one fourth of a cent a 50 pound, and refine sugars of low grade at an additional cost of one fourth a cent per kilo or one eighth of a cent a pound, whereas up to the present the first has been deemed unworkable, and the second impossible only at 55 an additional cost of at least ten cents per kilo or five cents a pound. 60 My new process for which I am applying for patent protection, is the following: The juice or molasses or syrup of the cane 65 or of the sugar beetroot, previously purified and concentrated by any of the usual systems, is heated at 85° C. is limed strongly, and then phosphoric acid and common alum is used. Afterwards sulphuric acid is added until there is a slight and only barely perceptible acid reaction. 70 Afterwards filter earth, paper pulp, or other efficient filtering material is added, and the liquid is filtered whilst hot. To 75 the juice thus filtered there is added animal or vegetable carbon, and the liquid is filtered again in separate filters, after which the liquid is ready to be submitted to the usual known processes to be made into sugar. 80 The residue, or parent molasses, resulting from the whitening of the sugar, is reboiled, with the object of producing exhausted molasses, by the manner well known, either in one or two operations. 85 The sugars resulting from these operations, properly refined, are remelted, and the syrups from this remelting are treated separately in the same manner as the first juices, but using only half the quantities of ingredients as employed in the treatment of the 90 original juices. 95 The proportions of ingredients used in the new process per 100 kilos of sugar produced are approximately: For cane juices or molasses or treacle or for beetroot sugar: 100 quicklime in the form of slacked lime 0.15

kilo; phosphoric acid in the form of dissolved paste 0.02 kilo; alum in solution 0.005 kilos; sulphur for the production of sulphuric acid 0.08 kilos; filter earth 0.715 kilos, or an equivalent quantity of other filtering material, animal or vegetable carbon 0.07 kilos; for the refined raw sugars half the quantities mentioned. The proportions are subject in individual cases to slight variations in accordance with the quality of the ingredients used, and to greater variations in the treatment of the juices in accordance with the variation of their purity, the proportions given being the maximum supposing the ingredients to be of good quality.

The new process differs considerably from that at present in use as a logical consequence of the considerations of a theoretical nature upon which it is based, which for their part are entirely distinct from existing ideas.

Their chief novelty lies in the use of sulphurization for the refining of sugar, and its application to the whole of the juices or syrups treated, the quantity of lime used, the quantity of lime being about 0.2% of the refined sugar produced, and that of sulphuric acid the amount necessary to bring about the required reaction. As a consequence, an entirely novel feature is the small quantity of bleaching carbon required, this being only a hundredth part of the quantity as present used. The combination and the quantities of ingredients used in the new process allow of a reduction in the cost of refining sugar to a tenth part of what it costs at present, as well as signify a notable simplification in the manufacture of refined sugars. This is revealed by a comparison of certain essential parts of the existing processes with those of the new method. The existing processes are characterized by the two stages by which the refined sugar is obtained, starting from the juices of the sugar cane or sugar beetroot. The manner of procedure is as follows:—The juices are crystallized, and by means of a centrifugal battery a first lot of sugar is obtained (product "A"). To exhaust the parent molasses derived from this first crystallization, it is recrystallized once or twice. To simplify the description, let us suppose that there is only one crystallization, and that its product is a sugar of low grade (product "B"). This product "B", unsuitable for refinement, is often melted up again, and the resulting syrup introduced into the original juice, to be transformed with the juice into product "A". The whole of product "A" is melted up again, and is then treated for the manufacture of refined sugar by means of a fresh crystallization. This form of manufacture requires two separate sets of apparatus for crystallization, of which that

which serves for the crystallization of product "A" must be of considerable capacity, as in its working there is included the recrystallization of product "B".

The same may be said in regard to the centrifugal batteries in which the sugar is separated from the parent molasses, as well as for all the accessories of these sections of the work. In the new process the original juice crystallizes after its treatment directly into refined sugar, and the same happens with the sugar of low grade, product "B". It results, therefore, that the number of apparatus is reduced to one half of those at present required, and the capacity required is also considerably less. The same applies when treating the manufacture of refined sugar from sugar of low grade and of inferior quality. Here again the recrystallization is proceeded with under present methods before the refined sugar is manufactured, whereas in the new process this complication is avoided. At present, starting from raw sugar of ordinary type (96° of polarization) from 5 to 10% of bleaching carbon is required. The new process requires only 0.05%, that is to say, from fifty to one hundred times less, to produce the same effect. The manufacture of refined sugar direct from the juices of sugar cane or sugar beetroot, which is at present regarded as impracticable from a commercial point of view, would require about 25% of bleaching carbon. The very reduced quantity of this carbon used in the new process, namely 0.01%, has now made this direct manufacture possible in the commercial sense. In view of the economy just mentioned, in both apparatus and bleaching carbons, the new process, with its ingredients, represents a cost so much lower than that of the present methods, that the costs of refining sugars, derived from one or other of the raw materials, are reduced to a tenth part of the present costs.

The essential points of novelty in the new process are first, the small quantity of alum used, which permits of the sulphurization of the juices when strongly limed and at a high temperature, the alum being used in this proportion for the purpose of securing the physico-chemical effect of affording an efficacious protection against the destruction of the sugar, as well as being a stimulant for the powerful absorption of the salts formed by the carbon used, the quantity of which does not reach a fiftieth part of that required in existing processes. And finally, the new process now allows of the manufacture of refined sugars directly from sugar cane or sugar beetroot juices, or from sugar of very inferior quality at a minimum cost, which is not possible under existing methods owing to the prohibitive cost.

The apparatus required for the application of the new process does not differ from

that commonly known already, and although it might be recommended that it would be better to use more perfected apparatus, yet by the help of suitable adaptations existing machinery could be used for the new process.

The nature of my invention having been described and specified, with the manner of putting it into practice, that which I claim 10 as my exclusive property and invention is:

1. A process for the manufacture of refined sugars direct from juices of sugar cane or sugar beetroot, which consists in heating the juices, liming the juices while at a 15 high temperature, adding to the juices a small quantity of alum and phosphoric acid,

sulphurizing the juices to bring about an almost imperceptible acid reaction, filtering the liquid, submitting the filtered liquid to the action of carbon, filtering the liquid, and 20 then submitting the filtered liquid to the ordinary processes for producing sugar.

2. In a process for obtaining refined sugars, in accordance with claim 1, the use of alum between the liming of the juices at a 25 high temperature and their sulphurization at a high temperature whereby the destruction of the sugar is avoided and the action of the carbon in its property of absorbing the salts formed is stimulated.

MAX RICHARD JOHANN SCHMID.
